UNITED STATES PATENT OFFICE

170,507

SHADOW BOX

Edward E. Mecus, Milwaukee, Wis., assignor to Dexter-Mahnke, Inc., Milwaukee, Wis., a corporation of Wisconsin

Application November 16, 1951, Serial No. 17,450

Term of patent 3½ years

(Cl. D29—20)

To all whom it may concern:

Be it known that I, Edward E. Mecus, a citizen of the United States, residing in Milwaukee, in the county of Milwaukee and State of Wisconsin, have invented a new, original, and ornamental Design for a Shadow Box, of which the following is a specification, reference being had to the accompanying drawing, forming a part thereof.

Portions of the drawing are lined to represent grooves or score marks.

I claim:

The ornamental design for a shadow box, substantially as shown and described.

EDWARD E. MECUS.
